UNITED STATES PATENT OFFICE.

ALBERT W. SMITH, OF HAVERHILL, MASSACHUSETTS, ASSIGNOR OF ONE-HALF TO FRANCIS D. BENEDICT, OF SAME PLACE.

STENCIL.

SPECIFICATION forming part of Letters Patent No. 402,281, dated April 30, 1889.

Application filed June 11, 1888. Serial No. 276,721. (No model.)

To all whom it may concern:

Be it known that I, ALBERT W. SMITH, a citizen of the United States, and a resident of Haverhill, in the county of Essex and State of Massachusetts, have invented new and useful Improvements in Dial-Painting Machines, of which the following, taken in connection with the accompanying drawings, is a specification.

This invention relates to improvements in dial-painting machines, for the purpose of spacing and numbering or otherwise marking watch-dials, and it is carried out as follows, reference being had to the accompanying drawings, wherein—

Figure 1 represents a plan view of the machine. Fig. 2 represents a cross-section on the line A B, shown in Fig. 1. Fig. 3 represents a cross-section on the broken line C D in Fig. 1. Figs. 4, 5, and 6 represent, respectively, a front view, vertical section, and bottom view of one of the vertically-movable stencils for spacing and marking the minute and hour divisions on the dial. Figs. 7, 8, and 9 represent, respectively, a side view, vertical section, and bottom view of one of the vertically-movable stencils for marking the numerals on the dial.

Similar letters refer to similar parts whenever they occur on the different parts of the drawings.

a in Figs. 1, 2, and 3 represents the base-plate of the machine, having on its under side a circular peg or projection, a', adapted to be inserted in a perforation in the table-top b, on which the base a is made to rest during the process of painting the dials, and by having the base a pivoted in this manner to the table-top b the entire machine may be turned more or less around the axis of the said peg or projection a' to suit the requirements of the operator, so as to place the machine from time to time in the most favorable position convenient for the operator to do the work.

c is a hand wrist-rest having a downwardly-projecting circular-pin, c', that is journaled in a bearing, c'', that forms a part of a horizontal bar, c³, that is adjustable in and out in a horizontal direction in a recess made in the base-plate a, as shown in dotted lines in Fig. 1 and full lines in Fig. 3, and by this arrange-

ment said hand or wrist rest may be adjusted out and in, as well as swung to any desired position, to suit the requirements of the operator. After being adjusted, if so desired, the 55 said hand or wrist rest may be secured in place by set-screws or equivalent devices, such being, however, not shown in the drawings.

On the top of the base-plate a are located two equal gear-wheels, d and e, the teeth of which mesh into each other, as shown in Figs. 1, 2, and 3, said gears having the respective downwardly-projecting spindles d' e', journaled in circular perforations in the base-plate a, as shown in Figs. 2 and 3, so that when 65 turning one of said gears around its axis a corresponding movement will be imparted to the other gear.

The gear e is the dial-support, on the top of which is temporarily secured the dial F while 70 in the act of being painted, said gear e having in its upper side a series of annular grooves, e'' e'', adapted to receive the downwardly-projecting pegs on the under side of the usual watch-dials. The dial F is held from turning around on the gear e by means of two pins, a central one, e³, that passes through the usual central dial-hole into a central cylindrical recess in the said gear e, and the pin e⁴, the lower portion of which is equal in size to the 75 lower end of the central pin, e³, and having its upper end reduced, so as to fit and project through the second-hand hole in the dial, as shown in Figs. 1, 2, and 3, and by this arrangement the dial, when thus placed in position 80 on the gear e, will partake of the rotary motion of the latter.

The gear d serves as a base and support for the marking or indexing device, and has for this purpose secured or attached to it the circular disk D', having twelve radial grooves, D'', in which are adjustably secured the radial bars G, G, adapted to slide out and in in said radial grooves and to be secured in position therein by means of spring-pressed pins 95 d'' d'', adapted to be locked in recesses g, g on the bars G, as shown in Fig. 2.

The radial bars G have in their outer ends vertical sleeve-bearings G', in which are vertically adjustable the spindles H, that are normally held in their highest positions (shown in Fig. 2) by the influence of springs h, sur-

rounding said spindles H, between the heads or buttons h' in their upper ends and the top of the bars G, or in any other equivalent manner.

5 The spindles H are held from turning around in their respective sleeve-bearings, as is usual in spindle devices of this kind. To the lower end of each spindle H is secured or made in one piece with it the templet or stencil I, composed of one or more feet or downward projections, i , with narrow intervening spaces i' , i'' between their lower ends, and a surrounding edge, i'' , with an intervening space or opening, i' , between its lower edge and that of the lower edges of the feet or projections i , as shown in Figs. 4, 5, 6, 7, 8, and 9. These templets or stencils are made in shapes according to the spacing, numbering, or lettering that is to be made on the dials. The stencil 15 represented in Figs. 4, 5, and 6 is intended for use in painting the circles and radial divisions for the hours and minutes on the main portion of the dial, and corresponding ones of smaller size are to be used for the same purpose on the second-hand part of the dial.

The templet or stencil represented in Figs. 7, 8, and 9 is for one of the numerals on the main portion of the dial, there being in all twelve of this kind, each shaped corresponding to one of the twelve numerals on such main portion of the dial. Smaller ones in a like manner are to be used in painting the reduced figures on the second-hand part of the dial. Other templets or stencils may be 35 used in a like manner for marking the name or make of the watch, such being made substantially like those above mentioned, only differing in form and shape according to the figure or design that is to be produced.

40 For the purpose of retaining the wheels d e in rigid positions while one of the stencils is pushed against the dial F, I employ a yielding or spring-pressed lever, E, the inner end of which is secured in a suitable manner to 45 the base-plate a , which lever has on its upper side a locking projection, E', adapted to project into any one of the twelve recesses e^5 on the under side of the gear-wheel e , as shown in Figs. 1 and 3.

50 In using the invention I prefer to use a number of the improved machines, all alike, except that the shapes of the stencils vary according to the marks, figures, or designs that are to be transferred in each to the dial. 55 Thus, for instance, I may use one machine for marking the minute and hour divisions, another for marking the divisions on the second-hand portion of the dial, another for marking the numerals from one to twelve on 60 the main portion of the dial, another for marking the numerals on the second-hand part of the dial, and another for marking the maker's name on the main portion of the dial, or in any other suitable or equivalent manner, although all these different kinds of marks or designs may be produced in a single machine simply by changing the stencils or templets

and changing the position of the dial on the gear e , according to the work that is to be done; but in practice I prefer to use a number of 70 machines, as above stated.

In using the machine, if the main portion of the dial is to be painted, I secure it in place on the gear e , as shown in the drawings—that is, concentric on top of said gear—the projections on the under side of the dial being inserted in any of the annular grooves e'' on the gear e , as described, and the dial prevented from moving on said gear by means of the pins e^3 and e^4 , passing through the respective central and second-hand holes of the said dial. During this operation the gear e is secured in place by means of the projection E' on the spring-lever E resting in one of the recesses e^5 on the under side of the gear e , and as the latter is positively geared to the gear d the latter and its stencil-carrier and stencils are also firmly held in accurate positions relative to the gear e and its dial F. The stencil or templet opposite to the center of the dial is then depressed by the operator pressing on the button h' until the under side of the templet rests against the top of the dial, when the operator paints, with a brush and suitable mastic enamel or color, on the dial in and through the openings i' , i'' in the templet, after which the latter is automatically raised to the position shown in Fig. 2 by the influence of its spring h as soon as the operator relieves the pressure on the button h' . The lever E is then depressed, causing the gear e to be liberated, and it and the gear d are then turned around, each one-twelfth of a revolution, until the next recess e^5 on the under side of the gear e is automatically 105 locked to the projection E' on the spring-lever E, when the operation is repeated on a new place on the dial, and so on until the entire circumference of the dial is painted. In 110 painting the second-hand the dial is secured to the gear in such a position that the hole for the second-hand coincides with that of the center of the gear e , the positions of the pins e^3 , e^4 being reversed, the radial stencil-carrying bars G, G being correspondingly moved 115 outward in their grooves D'' and secured in such positions by means of the spring-pressed projections d'' and the notches g on the under side of said bars G, when a similar operation takes place, and so on.

What I wish to secure by Letters Patent and claim is—

1. In a dial-painting machine, the intermeshing gears d , e , journaled to the base-plate a , the gear d having a series of vertically-movable templets or stencils adapted to be moved to and from the dial secured to the gear e , substantially as and for the purpose set forth.

2. In a dial-painting machine, the base-plate a and the dial-supporting gear e , journaled to it and having means for securing to it the dial to be painted, combined with the gear d , intermeshing with the gear e , a series

of radially-adjustable bars, G G, mounted on the disk D' on the gear d, and a series of vertically-movable templets or stencils arranged on spindles in said bars G and adapted to be moved to and from the dial that is being painted, substantially as and for the purpose set forth.

3. In a dial-painting machine, the base-plate a, having trunnion or pivot a', adapted to be inserted in a corresponding recess in the support b, combined with the dial-supporting gear e and the intermeshing gear d, journaled to the said base-plate, and the radially-adjustable and vertically-movable stencils or templets I, all arranged and combined substantially as and for the purpose set forth.

4. In a dial-painting machine, the dial-supporting gear e, having a series of annular grooves, e'', on its upper side, adapted to receive the projections on the under side of the dial, and having recesses on its upper side for receiving the pins e³ e⁴, for holding the dial in place on such gear, combined with the locking-lever E, having projection E', adapted to be locked into one of the recesses e⁵ on the gear e, substantially as and for the purpose set forth.

5. In a dial-painting machine, an intermittently-rotating dial-carrying device and an intermittently-rotating stencil-carrying device having radially-adjustable and verti-

cally-movable stencils or templets I, combined with an oscillating and horizontally-adjustable wrist-rest, substantially as and for the purpose set forth.

35

6. In a dial-painting machine, an intermittently-rotating templet-carrier and an intermittently-rotating dial-support and a locking and releasing device for securing said parts firmly in position during the operation of painting the figures, marks, or designs on the dial, substantially as set forth and described.

7. In a dial-painting machine, the templet-carrying gear e, journaled to the plate a and having a radially-grooved disk, D', a series of radially-adjustable bars, G, mounted in said grooved disk D', a locking device, as described, for securing said bars in position, and the spring-pressed spindles H, movable in bearings on said bars G and provided with stencils or templets I, substantially as and for the purpose set forth.

In testimony whereof I have signed my name to this specification, in the presence of two subscribing witnesses, on this 2d day of June, A. D. 1888.

55
